UNITED STATES PATENT OFFICE.

JOSEPH R. WESZELINOVITS, OF CHICAGO, ILLINOIS.

DYNAMO-ELECTRIC MACHINE.

No. 857,132.

Specification of Letters Patent.

Patented June 18, 1907.

Application filed July 14, 1906. Serial No. 326,212.

To all whom it may concern:

Be it known that I, JOSEPH R. WESZELINOVITS, a subject of the Emperor of Austria-Hungary, residing at Chicago, in the county of Cook and State of Illinois, have invented a certain new and useful Improvement in Dynamo-Electric Machines, of which, the following is a specification.

My invention relates to dynamo electric machines especially constant potential, compound wound current generators, and the object of the invention is to provide a constant potential machine which may be operated at a reduced speed when the demands upon it are lessened.

The invention also relates to motors, and the object of the invention in this connection is to provide a motor in which the speed will remain constant or, if desired, increase with increased load.

I obtain my object by the mechanism illustrated in the accompanying drawings in which:

Figure 1 is a view partaking of the nature of both a diagrammatic and a physical representation of a bipolar dynamo embodying my invention. The pole pieces and commutators are physically represented, but it will be understood that the armature coils are spread out circumferentially over a much greater distance than they would be in an actual machine. In practice they are much more condensed so that both the main and auxiliary coils may simultaneously occupy practically the same position in the magnetic field. Figs. 2 and 3 are purely diagrammatic views showing the arrangement of the windings and the connections to the commutators and to the exterior circuit. Fig. 3 shows in full lines the path of the current generated by the main coils of the armature while the machine is running at full speed. In Fig. 2 the machine is running at a somewhat reduced speed. In Figs. 2 and 3 a hand regulator is shown as it better illustrates the theory of operation. Fig. 4 is a central sectional elevation of a dynamo illustrating the invention. Fig. 5 is an end elevation of a portion of the machine indicating the construction of the regulator. Fig. 6 is a fragmentary section taken on line 6—6 Fig. 5. Fig. 7 shows a modified form of regulator adapted for a multipolar machine. Fig. 8 is an end view of an armature and regulator designed for use in a motor embodying my invention. Fig. 9 is a diagrammatic

view of the connections employed in such motor.

Similar numerals and letters refer to similar parts throughout the several views.

8, 9, represent the poles or field magnets, of a two pole generator, a two pole machine being here selected because of its simplicity of construction and the fact that it may be more easily described. It will be understood, however, that in practice the machines are ordinarily multipolar. The said magnets are mounted upon any suitable frame 10 which supports the armature shaft 11 which may be driven by means of pulley 12 or otherwise.

The armature which is designated in general in Fig. 4 by the numeral 13 is constructed upon the theory illustrated diagrammatically in Figs. 1 to 3 inclusive. Said armature comprises the two main coils designated generally by the letters *a* and *b*, and a corresponding number of auxiliary coils designated generally by the letters *c* and *d*.

Referring first to Fig. 1, the end *a'* of coil *a* is connected to the plus segment *e* of the main commutator, while the end *a''* of said coil is connected to the end *d'* of the auxiliary coil *d*. Coils *a* and *d* are, in reality, continuous, being wound in the same direction, so that one will assist the other in the induction of current. It will be understood that in practice coils *a* and *d* will be wound close together or will even be superimposed one upon the other, so that they may extend over a small space circumferentially in the armature, and therefore occupy, at any given moment, practically the same portion of the magnetic field. In practice, also, it is desirable that the coil *a* consist of heavy wire, and that the auxiliary coil *d* consist of heavy wire at the end *d'* and fine wire at the opposite end *d''*. The coils between the ends *d'* and *d''* should be graduated so that the change from the heavy wire at the end *d'* to light wire at the end *d''* will be gradual. The opposite side of the armature is wound in a similar manner, the principal coil *b* being connected at the end *b'* to the negative segment *f* of the main commutator, while the end *b''* of said coil is connected to the end *c'* of the auxiliary commutator coil *c*. The other ends *c''* and *d''* of the auxiliary commutator coils are connected respectively to the positive and negative segments *g* and *h* of the auxiliary commutator.

In the armature there are two rows of con-

tact-points which are designated in general by the reference letters i and j as shown in Figs. 1, 4 and 6. The contact-point i' at one end of the row i is connected to the coil d , at the point of union with coil a ; while the contact-point i^2 at the other end of said row is connected to the end turn d^2 of the auxiliary coil d . The contact-points between the ends i' and i^2 of the row are connected to intermediate turns of the auxiliary coil d . In a similar manner the contact-point j' at one end of the row j is connected to the coils b and c at the point of union thereof, while the contact-point j^2 at the other end of said row is connected to the turn at the end c^2 of the auxiliary coil c . The intermediate contact-points are connected to intermediate portions of said coil.

Referring especially to Fig. 1, a variable conductor x which is permanently connected to the main commutator segment f has a free extremity adapted to move over the row of contact points i , while on the other side of the armature a variable conductor y which has a free extremity adapted to move over the row of contact points j , is permanently connected to the segment e of the main commutator. The main brushes E and F contact the segments e and f respectively, while the brushes G and H contact the segments g and h respectively, of the auxiliary commutator. Brush E is connected through the conductor e' to the side E' of the load circuit after passing through a series exciting coil E^2 , (see Figs. 2, 3,). The other side F' (Fig. 1) is connected to brush F through the conductor f' . The auxiliary brushes G and H are connected through the conductors g' and h' , respectively, in series to the exciting coil k which consists preferably of many turns of fine wire.

As above indicated, the variable extremities of conductors x and y are adapted to be moved over the rows of contact-points i , j , and the construction is such that when the machine is running at full and normal speed, the movable ends of said conductors will connect with the contact-points i' and j' , respectively, but when the machine is running at its lowest limit, said ends will connect with the contact-points i^2 and j^2 respectively. At intermediate speeds, said movable ends occupy intermediate positions. From this it follows that when the machine is running at full speed, the auxiliary coils c and d will be cut out of circuit in so far as the main commutator is concerned.

I will now describe a governor suitable for operating in the manner above outlined, the variable conductors x and y .

Referring more particularly to Figs. 4, 5 and 6, a disk 14 carrying two segments 15 is located at the side of the armature, which is represented in general by the reference numeral 13. Arranged in a quadrant of a cir-

cle in one of said segments are the contact points j above mentioned, with the contact point j' at the end farthest from the axis of shaft 11, and the point j^2 at the end nearest to said shaft. In a similar manner the contact points i are arranged in a quadrant upon the other one of segments 15. A controller weight-arm 16 is pivoted to segments 15 at lugs 17 which are located at the center of the circle of contact points i and j . Arms 18 are rigidly connected with arms 16 and carry at their free extremity friction rollers 19 adapted to press upon the washer 20 which is slidable lengthwise upon shaft 11, as shown in detail in Fig. 7.

A compression spring 21 is interposed between washer 20 and the collar 22 which is adjustable upon shaft 11 by means of the setscrew 23, or otherwise. The parts are so arranged that when at full speed the weight-arms 16 tend to arrange themselves at right angles to the axis of shaft 11, they will move to a position where they will make contact with points i' and j' , overcoming the pressure of spring 21. When however, the speed decreases to a minimum, said springs will overcome the centrifugal action in arms 16, and will tend to swing them more nearly parallel with the axis of shaft 11, so that said arms will be in contact with the points i^2 and j^2 at the opposite end of the rows. The inner end of an arm 16 is designed to be connected with the conductor y (Fig. 1) and the inner end of the other arm to conductor x . In the operation of the governor, therefore, a high speed of rotation will swing arms 16 to contact-points i' and j' which will cut out auxiliary coils c and d as far as the main commutator is concerned, while a reduction in speed will permit the spring 21 to swing the governor arms 16 in the opposite direction and cut in more and more turns of coils c and d in proportion as the speed decreases. In operation, to trace the path of the various currents, the main armature coils a and b , and more or less of the auxiliary coils c and d are in parallel with the main commutator segments e and f . From the main segments the circuit is, of course, completed through the exterior line, which in the case of a generator is a consumption or load circuit and in the case of a motor, a supply circuit. When the machine is compound wound, as illustrated, the circuit outside of the main brushes will also include the series exciting coil E^2 . The path of the main including current at an intermediate speed is indicated in heavy lines in Fig. 1 and at full speed in heavy lines in Fig. 3.

Now to consider the exciting coil k and its source of current. It will be noted that all of the current generated in the main coils a and b does not pass into the main commutator, but part of it divides at the points where the variable conductors x and y con-

nect with the contact points *i* and *j*. Referring especially to Fig. 3, this divided current passes from conductors *x* and *y* to the coils *c* and *d* respectively and thence through the auxiliary commutator segments *g* and *h* to the exciting coil *k* through which the circuit is completed.

It will thus be seen that the current flowing through the main commutator always flows through the main armature coils and more or less of the auxiliary coils, depending upon the speed of the machine. The current generated in the auxiliary coils beyond the point of connection with the variable conductors *x* and *y*, is in the nature of an additional current for additionally exciting coil *k*. In other words, coil *k* always has an additional number of turns (in the auxiliary coils) acting to generate current for it.

It will be noted that so far as the current passing through the auxiliary brushes *G* and *H* is concerned it always travels through the entire length of both main and auxiliary coils. Thus the number of active turns so far as the auxiliary commutator is concerned is constant and consequently the greater the speed of the machine, the greater will be the exciting effect of the shunt coil *k*, which derives its current from the auxiliary commutator. In brief therefore, when the speed of rotation is reduced, the number of acting turns leading to the main commutator for impressing E M F to the main line is increased, but the number of turns leading through the auxiliary commutator to the exciting coil *k* remains the same. Now, although the increasing of the number of acting turns in circuit with the main commutator would tend to increase the E M F, such E M F does as a matter of fact remain constant by reason of the fact that the speed of rotation of the armature is decreased; for it is evident that the reduction in speed not only decreases the field strength but decreases the induction (owing also to decreased rotation of the main coils) and also increases the internal resistance of the armature by reason of the increased number of acting turns in circuit with the main commutator. A dynamo constructed upon this principle will therefore give a constant voltage but may be run at a reduced speed when the demands upon it are lessened.

Although in Figs. 4, 5 and 6 a bipolar machine is illustrated, a machine having a much larger number of poles may be regulated by means of a governor only slightly modified.

In Fig. 7 a suitable modified governor is shown, it having a plurality of concentric rows *j*, *k*, *m*, *n*, *o*, of contact points instead of the single row *j*. By employing four segments 15, and thus placing a plurality of contact points on each, a machine having fifty or more auxiliary coils may be governed.

It will be understood that this invention is applicable to direct current motors as well as generators, and a motor embodying this invention is illustrated in Figs. 8 and 9. Referring to Fig. 9, which shows diagrammatically the connections for a two pole motor, *a* and *b* represent the main commutator coils, as before, *c* and *d* represent the auxiliary coils, *e* and *f* the main commutator segments, *g* and *h* the auxiliary commutator segments, *i* and *j* the rows of contact points connected to different portions of coils *c* and *d*. *x* and *y* represent the variable conductors which are connected to the main commutator segments *e* and *f* as before. The manner of connection of the auxiliary coils *c* and *d* however, differs from the connection in the generator in that the auxiliary commutator segments *g* and *h* are connected through the points *i*³ and *j*³ to the contact points *i*⁷ and *j*⁷ nearest to the main coils *a* and *b* instead of to the points *i*² and *j*² as in the generator. The governor is so arranged that as the drag on the motor shaft due to increased load increases it will throw conductors *x* and *y* toward ends *i*⁷ and *j*⁷ of the row of contact points *i* and *j*, and as the drag increases, toward ends *i*² and *j*². Thus as the drag increases, the auxiliary coils *c* and *d* will be proportionately cut out of circuit. With this kind of connections the current entering from the positive one *P* of the two supply mains *N* and *P* will pass through segment *e* and conductor *y* through more or less of coil *c* depending respectively as the load on the machine decreases or increases. At point *j*³ the current will divide, to be reunited at point *i*³, one path being through coil *a*, another through coil *b* and another through the auxiliary commutator segments *g* and *h* and exciting coil *k*. From point *i*³ the current will pass through more or less of coil *d*, depending upon whether the load upon the machine decreases or increases. From coil *d* the current flows through conductor *x* and segment *f* to the supply main *N*. Thus it will be seen that increasing the load (which decreases the number of auxiliary turns of coil in action) decreases the resistance in circuit with the exciting coil *k* and hence increases the currents through it and correspondingly increases the field.

At the same time, the cutting out of the resistance increases the current in the main armature coils *a* and *b*. Consequently as the load increases, the field strength becomes greater and also the current consumed in the main coils becomes greater, thus giving greater torque at the same or greater speed. A suitable form of regulator for a motor having this winding is shown in Fig. 8. Here the disk 14^a which forms a part of the armature and revolves with it, is loose upon shaft 11^a. The torque of the armature is imparted to said shaft by means of springs 24 which are attached at 130

one end to said disk and at the other to arms 25, 26 rigidly secured to said shaft. Arranged concentrically with shaft 11^a in such position that arms 25, 26 will pass over them are the rows of contact points *i* and *j* above described. Said arms have upon them suitable conductors, not shown, connecting them to the main commutator segments *e* and *f* respectively. They correspond therefore to the arms *x* and *y* shown in the diagrammatic view Fig. 9. The contact points *i'* and *j'* are at the end of the row farthest ahead, considering the direction of rotation of the armature, indicated by the arrow Fig. 8.

15 In the operation of the regulator when the load on the motor is light, and the backward drag of shaft 11^a is least, spring 24 will be only lightly strained and said arms will come to a balance over contact points *i'* *j'* but as 20 the load increases, the shaft and arms thereon will drag farther behind, thereby stretching the springs and causing the arms 25 and 26 to slip back toward the end *i'* and *j'* of the rows of contact points.

25 1. In a dynamo electric machine, the combination, with the field magnets of an armature winding having two kinds of connections, one an invariable connection always including the same number of conductor 30 turns and leading to the field magnets for exciting them, and the other a variable connection including a variable number of conductor turns for delivering current to the load circuit.

35 2. In a dynamo electric machine, the combination, with the field magnets of an armature winding having two kinds of connections, one an invariable connection always including the same number of conductor 40 turns and leading to the field magnets for exciting them, and the other a variable connection including a variable number of conductor turns for delivering current to the load circuit and means for varying the number of 45 conductor turns in the armature acting to deliver current to the load circuit.

3. In a dynamo electric machine, the combination, with the field magnets of an armature winding having two kinds of connections, one an invariable connection always including the same number of conductor 50 turns and leading to the field magnets for exciting them, and the other a variable connection including a variable number of conductor turns connected to the exterior circuit, the number of turns acting upon the exterior circuit depending upon the speed of the dynamo—or the load of the motor, the greater the speed or load the less the number of acting turns and vice versa.

4. In a dynamo electric machine, the combination, with the field magnets of an armature winding having a main and an auxiliary coil connected together in series, each coil 65 comprising a plurality of turns of a suitable

conductor; two kinds of connections to said armature winding, one an invariable connection always including all of the turns of both main and auxiliary coils, and the other a variable connection and always including 70 the principal coil and more or less of the auxiliary coil, depending respectively as the speed of the machine decreases or increases, the invariable connection leading to the field magnets for exciting them, and the variable 75 connection leading to the load circuit, and means for varying said variable connection.

5. In a dynamo electric machine, the combination, with the field magnets of an armature winding having a main and an auxiliary 80 coil connected together in series, each coil comprising a plurality of turns of a suitable conductor; and two kinds of connections to said armature winding, one an invariable connection always including all of the turns 85 of both main and auxiliary coils, and the other a variable connection and always including the principal coil and more or less of the auxiliary coil, depending respectively as the speed of the machine decreases or increases, the invariable connection leading to the field magnets for exciting them, and the variable 90 connection leading to the mains.

6. In a dynamo electric machine, the combination, with the field magnets of an armature winding having a main and an auxiliary 95 coil connected together in series, each coil comprising a plurality of turns of a suitable conductor; two kinds of connections to said armature winding, one an invariable connection always including all of the turns of both 100 main and auxiliary coils, and the other a variable connection and always including the principal coil and more or less of the auxiliary coil, depending respectively as the speed of the machine decreases or increases, the invariable connection leading to the field magnets for exciting them, and the variable connection leading to the load circuit; and an automatic governor for varying said 105 variable connection.

7. In a dynamo electric machine, the combination, with the field magnets of an armature winding having a main and an auxiliary coil connected together in series, each coil 115 comprising a plurality of turns of a suitable conductor; two kinds of connections to said armature winding, one an invariable connection always including all of the turns of both main and auxiliary coils, and the other a variable connection and always including 120 the principal coil and more or less of the auxiliary coil, depending respectively as the speed of the machine decreases or increases, the invariable connection leading to the field magnets for exciting them, and the variable connection leading to the load circuit; and a fly ball governor for automatically varying 125 said variable conductor.

8. In a dynamo electric machine, the com- 130

bination, with the field magnets of an armature winding having two kinds of connections, one an invariable connection always including the same number of conductor turns and leading to the field magnets for exciting them, and the other a variable connection including a variable number of conductor turns for delivering current to the load circuit, said variable and invariable connections having conductor turns in common.

9. In a dynamo electric machine, the combination, with the field magnets of an armature winding having two kinds of connections, one an invariable connection always including the same number of conductor turns and leading to the field magnets for exciting them, and the other a variable connection including a variable number of conductor turns for delivering current to the load circuit, said variable and invariable connections having conductor turns in common and said variable connections always comprising a portion of said invariable connections.

10. A dynamo having a closed coil armature with a variable number of turns constituting the main inducing coils, and auxiliary coils for exciting the fields.

11. A dynamo having a main commutator connected to the main line terminals, an auxiliary commutator connected to the field exciting coil, a fixed number of armature turns in circuit with said auxiliary commutator, and a variable number of armature turns in circuit with said main commutator.

12. A dynamo having field magnets, a main commutator whose brushes connect with the main line terminals, an auxiliary commutator whose brushes connect with the field exciting coil, an armature coil connected to the segments of said auxiliary commutator, and means for throwing more or less of said armature coil into connection with the segments of said main commutator.

13. A dynamo having field magnets, a main commutator, whose brushes connect with the main line terminals an auxiliary commutator whose brushes connect with the field exciting coil, an armature coil connected to the segments of said auxiliary commutator, and a centrifugal governor for throwing more or less of said armature coil into connection with the segments of said main commutator.

14. A dynamo having field magnets, a single armature shaft, a main and an auxiliary commutator rotating in unison with said shaft, a main commutator whose brushes connect with the main line terminals an auxiliary commutator whose brushes connect with the field exciting coil, an armature coil connected to the segments of said auxiliary commutator, and means for throwing more or less of said armature coil into connection with the segments of said main commutator.

15. A dynamo having field magnets, a

main commutator, whose brushes connect with the main line terminals an auxiliary commutator whose brushes connect with the field exciting coil, an armature coil connected to the segments of said auxiliary commutator, a row of contact points connected with different portions of said armature coil and a controller for connecting the main commutator segments with different ones of said contact points.

16. A dynamo having field magnets, a main commutator, whose brushes connect with the main line terminals an auxiliary commutator whose brushes connect with the field exciting coil, an armature coil connected to the segments of said auxiliary commutator, a row of contact points connected with different portions of said armature coil, a controller for connecting the main commutator segments with different ones of said contact points and self operating means for operating said controller.

17. A dynamo having field magnets, a main commutator, whose brushes connect with the main line terminals an auxiliary commutator whose brushes connect with the field exciting coil, an armature coil connected to the segments of said auxiliary commutator, a row of contact points connected with different portions of said armature coil, a controller for connecting the main commutator segments with different ones of said contact points, a controller for connecting the main commutator segments with different ones of said contact points, and a centrifugal device for operating said controller.

18. A constant potential, variable speed electric generator having a single armature consisting of main coils and additional turns of conductor connected to the end of each of said main coils an exciting coil in series with the main coils and all of their additional turns, and load brushes adapted to be connected in series with all of said main armature coils and a varying number of said additional coils.

19. In a dynamo electric machine, the combination, with the field magnets of an armature winding having a main and an auxiliary coil connected together in series, each coil comprising a plurality of turns of a suitable conductor; and two kinds of connections to said armature winding, one an invariable connection always including all of the turns of both main and auxiliary coils, and the other a variable connection and always including the principal coil and more or less of the auxiliary coil, and a governor for controlling the variable connection.

20. In a dynamo electric machine, a main and an auxiliary commutator, an exciting coil connected to said auxiliary commutator, and armature coils connected in series with said auxiliary commutator, a portion of said armature coils being connected in parallel

between different segments of said main commutator.

21. In a dynamo electric machine a main and an auxiliary commutator, and armature coils connected in series with said auxiliary commutator, a variable amount of said armature coils being connected in parallel between different segments of said main commutator and an exciting coil connected to said auxiliary commutator.

22. In a dynamo electric machine a main and an auxiliary commutator, armature coils connected in series with said auxiliary commutator and a variable amount of said arm-

ture coils being connected in parallel between 15 different segments of said main commutator, an exciting coil connected to said auxiliary commutator and means for varying the amount of said armature which is in parallel between the segments of the main commutator. 20

In witness whereof, I have hereunto subscribed my name in the presence of two witnesses.
